UNITED STATES PATENT OFFICE.

WILLIAM M. BAUER, OF CHICAGO, ILLINOIS.

PNEUMATICALLY-PLAYED PIANO.

Application filed May 11, 1922. Serial No. 560,033.

To all whom it may concern:

Be it known that I, WILLIAM M. BAUER, a citizen of the United States, residing at Chicago, in the county of Cook and State of Illinois, have invented a new and useful Improvement in Pneumatically-Played Pianos, of which the following is a specification.

In pneumatically-played grand pianos, 10 the motor (ordinarily electric), and the vacuum-pump operated thereby and contained in a pump-box are commonly located in the rear or tail end of the piano-casing, where they are very inconveniently 15 accessible for purposes of removal, adjustment and repairing. Moreover, as the motor is supported in place, its operation is attended with objectionable noise.

The primary objects of my improvement 20 are to so support the motor in place as to render its operation comparatively noiseless; to render it conveniently accessible and also to facilitate access to the pump for the named purposes.

25 These objects are accomplished by the means hereinafter described and illustrated in the accompanying drawings, in which—

Figure 1 is a broken bottom plan view of a grand-piano casing showing the motor 30 and pump-box in operative position therein and supported in accordance with my improvements; Figure 2 is a partly dotted and sectional side view regarded from the adjacent side of Fig. 1, showing the hinged 35 motor and pump-box carrying frame in elevation in its normally raised position and by dotted representation in the act of being lowered; Figure 3 is a section on line 3—3, Fig. 1, showing the motor on its slidably- 40 adjustable supporting rods in a hinged frame in the relatively larger hinged frame carrying the pump-box and the motor-supporting frame; Figure 4 is a broken top plan view of the larger or combination 45 frame, showing the spring-retracted motor on its slidable supporting rods in the smaller frame, which is hingedly supported in the larger frame; and Figure 5 is a broken side view of the showing in Fig. 4, 50 but representing the smaller motor-carrying frame in its lowered position on the larger frame.

The piano-casing 6 shown is like that illustrated in my Patent No. 1,171,921 dated 55 February 15, 1916. On a stationary rail 7 extending across the wider, forward part

of the under side of the casing is hinged at one end a suitably braced frame 8 formed to fit inside the rear part of the casing and reach short of the end thereof, where it is 60 provided with means, such as a pivotal button 9, for releasably securing it in its normal, raised position. The box 10 into which an air-conduit 10^a leads, as usual, and which contains the usual vacuum pump, of which 65 only the drive-pulley 11 is shown (Fig. 1), is secured in the frame 8 to one side of its longitudinal center. In the opposite side of this frame is hinged at one end a relatively smaller frame 12, shown of three-sided construction and having its side-bars 70 releasably fastened at their ends, as by screws, to the adjacent end-bar of the frame 8.

The motor 13 is supported on the smaller 75 frame 12, preferably in the manner most clearly represented in Fig. 4. The supporting means shown comprise a head 14 of any suitable material, but which I prefer to form of wooden laminae, the head containing in one face a recess 15 having sound-deadening cushioning material 16, such as rubber, in its opposite end-portions, through which the feet on the motor-casing are bolted to the head; and the head is carried on a pair of parallel rods 17, also preferably of wood, passing with a drive-fit through openings near its opposite ends. These rods bear at their ends on the side-bars of the frame 12, where one of them is confined by 80 clips 18, rigidly secured, each by a pair of screws, to these side-bars, the other rod being similarly confined by clips 19 pivoted to the side-bars. The under face of the 85 end of each clip which bears on a rod is cushioned at 20, as with felt, and where the rods bear against the frame side-bars, the latter are also cushioned, preferably with felt-covered rubber, as shown in Fig. 90 3, to enable the rods to slide noiselessly in 95 their bearings under the motor-retracting tendency of the spring 21 connecting the head 14 with the adjacent side-bar of the larger frame 8, for maintaining taut the belt 22, which gears the motor-shaft to the 100 pump drive-pulley 11. Sockets 23 and 24 are represented in Fig. 1 for connecting electrical conducting-cords (not shown) respectively with the motor and the supply 105 of current in the house.

In a player-piano of the present class, the motor requires more frequent inspection, for 110

any of the aforesaid purposes, than the pump-mechanism, for which reason I have adapted the motor to be lowered on its hinge, from its normal position into depending vertical position, independently of the pump-box. For so lowering the motor, after removing the belt 22, the screws in the ends of the side-bars of its frame are withdrawn, when the frame will turn on its 10 hinges into hanging position, in which it may be propped by a box or other suitable medium (not shown) placed underneath its lower end, and wherein it is conveniently accessible. To enable the motor to be removed from its supporting frame 12, as for replacing it by another or for other desired purpose, this may be readily accomplished, with the frame lowered and after disconnecting the spring 21, upon turning the 15 clips 19 outwardly on their pivots and lifting the rod 17 out from under its end-confining clips 18. No means are really necessary to be provided for the purpose of the clips 18 and 19 (except that of guiding the motor under the retractive force of the spring 21), but the latter are desirable by way of precaution to prevent the motor from bearing against and maybe injuring or even breaking the sounding-board of the 20 piano when in upside down position, as it is sometimes placed in course of shipment. For inspection of the pump-mechanism, and of the motor at the same time, if desired, without lowering the latter from its position 25 in the frame 8, the latter, on being released by turning the button 9, is lowered on its hinges into inclined position, without necessarily removing the belt 22 or disconnecting the belt-tautening motor-retracting 30 spring. In this lowered position of the frame 8, the pump-mechanism may not only be repaired or adjusted, and the motor likewise, if required, but the playing of the instrument may be proceeded with, thereby to 35 ascertain whether the adjustments have been properly made, thus without requiring the pump-mechanism to be replaced into and fastened in normal position for the testing and being again, or repeatedly removed and 40 replaced until the adjustments are found to be faultless. The latter are the requirements for testing in these piano-players wherein the motor and pump-containing box are immovably secured in place in the piano-casing, where their inspection, adjustments 45 and repairs are rendered inconvenient and difficult, since the workmen have to handle their tools in performing the work in strained and abnormal positions non-conducive to either comfort or efficiency. On 50 the other hand, as will be seen, my improvement avoids these objections by rendering the mechanisms conveniently accessible for all purposes and as easily replaceable after 55 being removed from their normal positions.

I realize that considerable variation is possible in the details of construction and combinations of parts herein shown and I do not intend to limit my invention thereto except as pointed out in the appended 70 claims, in which it is my intention to claim all the novelty inherent in my invention as broadly as permissible by the state of the art.

I claim:

1. In a pneumatically-played piano, in combination with the piano-casing, a frame hingedly supported in said casing to be lowered on the hinges from its normally-raised position, a head on rods extending through cushioned bearings on the side-bars of said frame in which said rods are slidably supported at their end-portions, a spring-retracted motor secured on said head in cushioned bearings thereon, and a pump-containing box supported in said casing and having the pump-shaft geared to the motor. 75
2. In a pneumatically-played piano, in combination with the piano-casing, a frame hingedly supported in said casing to be lowered on the hinges from its normally-raised position, and a pump-containing box and a motor supported on said frame, the motor being geared to said pump for driving it. 80
3. In a pneumatically-played piano, in combination with the piano-casing, a frame hingedly supported in said casing to be lowered on the hinges from its normally-raised position, a pump-containing box supported on said frame, a relatively smaller frame hingedly supported on said first-named frame to be lowered independently thereof from its normally raised position, and an electric motor on said smaller frame 100 and having its shaft belt-connected with the pump-shaft. 105
4. In combination with a piano-casing, motor-supporting means therein comprising a solid head, rods extending through and tightly secured in the end-portions of said head, said rods being longitudinally movable in bearings, and a pump-operating motor secured to a face of said head to extend therefrom between the rods. 110
5. In combination with a piano-casing, motor-supporting means therein comprising a solid head on rods, said rods being longitudinally movable in bearings, and a pump-operating motor secured on said head. 115
6. In combination with a piano-casing, motor-supporting means therein comprising a solid head on rods extending through cushioned bearings in which the rods are slidably supported at their end-portions, and a pump-operating motor secured on said head. 120
7. In combination with a piano-casing, motor-supporting means therein comprising a solid head formed of wooden laminae, 125

rods extending through and tightly fitting openings in said head and slidably supported at their end-portions in cushioned bearings, and a pump-operating motor secured on said head.

8. In combination with a piano-casing, motor-supporting means therein comprising a solid head on rods, said rods being longitudinally movable in bearings and a pump-operating motor secured on said head, said supporting means being hingedly supported in said casing.

9. In combination with a piano-casing, motor-supporting means therein comprising a head on rods extending through cushioned bearings in which the rods are slidably supported at their end-portions, clips stationarily secured to extend over corresponding end-portions of the rods in their bearings, pivotal clips extending over the opposite end-portions of the rods in their bearings, and a pump-operating motor secured on said head.

WILLIAM M. BAUER.
